UNITED STATES PATENT OFFICE.

WILLIAM H. MILLER, OF CLEVELAND, OHIO.

MIXING ATTACHMENT FOR INTERNAL-COMBUSTION ENGINES.

Application filed January 4, 1921. Serial No. 434,903.

My invention relates to a mixing attachment for an internal combustion engine, the object being to provide a simple mixing device which may be readily clamped between two engine parts through which the combustible mixture must pass and whereby a swirling and effective admixture will be effected as the mixture is being drawn into the engine.

10 In the drawing accompanying this application, Fig. 1 is an enlarged view of a portion of a carburetor and manifold, together with my improved mixing device secured in place therein. Fig. 2 is a plan or top view 15 of the mixing device itself, and Fig. 3 is a side elevation of the device shown in Fig. 2. Figs. 4 and 5 are sectional and bottom views, respectively, of a modified form of the invention. Fig. 6 illustrates a further modification 20 in which the device is shown as formed of separable parts instead of being made in integral form as in Fig. 1.

The invention comprises a relatively thin flat ring having a series of upright deflecting vanes 3 arranged in a circle at one side thereof, each vane 3 being bent and curved inwardly at one of its upper end corners toward the center of ring 5 so as to produce a curved deflecting point 4 opposite the inner edge of the ring. A deflecting or spreading member is also provided at the bottom side of the ring beneath opening 5 and in Figs. 1, 2, 3 and 6 this spreading member comprises member 6 having a frusto-conical shape having a large number of small openings or perforations 7 in its side and being further provided with slightly larger openings 8 at its base where joined with ring 2. Openings 8 are also especially located in reference to the inturned extremities 4 so that the mixture trapped on the outside of cone 6 will pass in streams through openings 8 and impinge and be deflected spirally by the points or inturned extremities 4. Thus, openings 8 are located immediately beneath the turned corners 4, and the cone 6 is spaced apart from the inner face 9 of the connecting branch 10 of the carburetor, see Fig. 1 wherein ring 2 is shown clamped between a flange 11 on the carburetor branch 10 and a flange 12 on the engine manifold 13. The central portion of the mixing device is practically open and unobstructed, but the perforated cone 6 55 acts to break up the passing fluid or mix-

ture and to deflect them inwardly in fine streams toward the center and also to create other streams by means of openings 8 directly beneath the bent extremities 4. In this way, a swirling mixing movement of 60 the fluid or vapors is created during the operation of the engine and a perfect admixture delivered through the engine intake manifold 13. Actual tests show that the engine can be operated with a much higher degree of efficiency using a device of this character as compared with an engine not so equipped.

In Figs. 4 and 5, I show a ring 15 with bent vanes 16 corresponding to the showing 70 in Figs. 1 to 3, but in lieu of employing a perforated cone I show a flat ring 17 having a central conical spreader 18 connected by radial arms 19 to the ring. In Fig. 6 I show a ring 20 with bent or twisted vanes 75 21, a perforated cone 22 made in a separate piece, and the separate ring 17 with its conical spreader 18 interposed between ring 20 and cone 22.

The device is primarily intended for use 80 in internal combustion engines but it may also be used to promote admixture of other fluids than gasoline and air, and therefore, no limitation in this respect or to the place of use of the device is intended.

85 What I claim is:

1. A mixing attachment for an internal combustion engine, comprising a flat ring having a circle of vanes at one side thereof, the end extremities of said vanes being bent 90 inwardly on curved lines; and a tapered spreading member at the opposite side of said ring having openings at its base in line with said inwardly-projected extremities.

2. A mixing device for use in connection 95 with the manifold of an internal combustion engine, comprising a member provided with a depending portion having a central opening, a plurality of upwardly extending vanes on the opposite side of said member and integral therewith, said vanes being turned 100 inwardly at an upper corner to form a substantially hollowed surface, the turned in corners overlapping the opening but terminating short of the center thereof.

105

Signed at Cleveland, in the county of Cuyahoga, and State of Ohio, this 29th day of December, 1920.

WILLIAM H. MILLER.
